(57) **CLAIM**

The ornamental design for a cassette for peritoneal dialysis cycler, as shown and described.

DESCRIPTION

FIG. 1 is a top perspective view of a cassette for peritoneal dialysis cycler showing our new design;

FIG. 2 is a front elevation view of the cassette of FIG. 1

FIG. 3 is a rear elevation view of the cassette of FIG. 1;

FIG. 4 is a right side view of the cassette of FIG. 1;

FIG. 5 is a left side view of the cassette of FIG. 1;

FIG. 6 is a top plan view of the cassette of FIG. 1; and,

FIG. 7 is a bottom plan view of the cassette of FIG. 1.
